UNITED STATES PATENT OFFICE

HARRY J. MOREY, OF SYRACUSE, NEW YORK, ASSIGNOR TO PASS & SEYMOUR, INCORPORATED, OF SYRACUSE, NEW YORK, A CORPORATION OF NEW YORK

SINGLE FLUSH RECEPTACLE

Application filed March 7, 1925. Serial No. 13,838.

This invention relates to electric attachment receptacles and more particularly to single flush receptacles adapted to be mounted in a wall box and to receive an attachment plug therein.

It is a general object of this invention to provide a novel and improved form of flush receptacle.

More particularly it is an object of this invention to provide in a flush receptacle a single unitary insulating structure adapted to receive therein the stationary contacts and having the binding posts or circuit terminals arranged one on either side of the block.

15 It is a further object of this invention to provide in a flush receptacle a single insulating member adapted to receive the stationary contacts or springs and the binding posts or circuit terminals, a single screw serving to hold each contact and its binding post in position.

A still further object of the invention consists in the provision of a flush receptacle in which the current carrying parts of opposite 25 polarity are positioned at a maximum distance apart without the interposition of any baffles, flanges or other projections and in which the recesses for retaining the two contacts are entirely isolated and open upon 30 opposite faces of the porcelain.

In the accompanying drawings and following specification there is disclosed by way of example only, a single illustrative embodiment of the present invention with the understanding however that various changes 35 may be made therein by those skilled in the art, such as in the arrangement, proportion, form and size of the various parts without departing from the spirit of the invention as 40 set forth in the appended claims.

In the said drawings:

Fig. 1 is an elevation of the receptacle as positioned in a wall and covered by a face plate;

45 Fig. 2 is a side elevation thereof;

Fig. 3 is a vertical central section thereof;

Fig. 4 is a section on line 4—4 of Figure 2 looking in the direction of the arrows;

50 Fig. 5 is a section on line 5—5 of Figure 2; and

Fig. 6 is a perspective view of one of the contacts and its associated binding post.

The flush receptacle disclosed in this application is adapted to receive a single push plug but it is obvious that with slight modifications it could be adapted to receive two or more. It comprises the porcelain or other insulating block 10 which is generally shaped as a parallelopiped having on one of its long narrow faces the projecting circular boss 11. 55 This boss extends beyond the face which carries it and is adapted to project through the face plate 12 which serves to cover all of the rest of the porcelain block and the conduit box which receives it and provides a 60 finish for the receptacle.

A pair of metal straps 13 are set into the front face of the porcelain adjacent the boss 11 and extend beyond the ends thereof and are provided with holes 14 to receive screws 70 to attach the porcelain block to a conduit or wall box, as is usual with this form of device. These straps 13 are fastened to the insulating block by the screws 15 passing through the block from the back to the front 75 and threaded into the straps. The heads of the screws 15 are set down in the counterbores 16 in the block. Screws 17 serve to secure the face plate 12 to the straps 13, as best shown in Figure 3. 80

The circular boss 11 is provided with the T-shaped slots 18, as is common in receptacles, adapted to receive either parallel blade, tandem blade or polarized plugs and each of these slots enters into a separate substantially rectangular recess 19 in the insulating block below the boss. These recesses open outwardly into opposite side faces of the block, as best shown in Figure 4, and have as their top walls the under side of the 90 boss 11. They are separated from each other by a substantial transverse partition 20 almost as thick as the distance between the parallel blades of a plug. It will be seen that the recesses which are adapted to receive the 95 stationary contacts, which are of opposite polarity, are entirely isolated from each other and have their openings disposed on opposite side faces of the insulating block, thus affording a maximum of insulation and pre- 100

venting any possibility of short circuiting. Into each of the recesses 19 is placed a universal spring contact member such as best shown in Figure 3, which is adapted to receive one of the blades of an attachment plug 5 of any of the mentioned types.

This particular form of stationary contact is well known and need not be further described except to state that it is formed of a single piece of spring metal bent as shown, 10 and has a base member 22 arranged in a plane at right angles to the direction of movement of the attachment plug upon being inserted, which base is integral with the single spring 15 arm but separated from the two side arms 23 carried thereby so that the projecting tab 24 on the circuit terminal 25 may be placed above it and between it and the arms 23, as best shown in Figure 5. These two parts are 20 assembled together and the arms 23 are long enough to exert a slight pressure on the surface of the tab 24 to hold the parts properly assembled while they are slipped into position in the recess 19 and the screw 26 passed 25 through the opening in the base 22 and threaded into the hole in the tab 24. The head of the screw 26 is set in a counter-bore in the back of the porcelain block and is preferably covered with a sealing wax while the 30 shank of the screw passes through a suitable aperture in the porcelain block and enters the thread in the tab 24 and thus securely holds the binding post and the spring contact member in position.

35 The size and shape of the recesses in the porcelain block are such as to prevent any substantial twisting of the contacts about their retaining screws and in order to further prevent this the exposed parts 26' of the 40 binding posts are arranged in a plane at right angles to the tabs 24 and offset from the plane of the base thereof, as best shown in Figure 6, and rest flat against the outer surfaces of the porcelain block, as shown in Figure 4. The 45 wings 27 are provided on the binding posts to assist in the wiring operation and to hold the loop of wire beneath the binding screws 28. Suitable channels 29 are provided in the walls of the recesses 19 to accommodate the ends of 50 these binding screws 28. Since the binding posts have their portions 26' arranged flat against the outer surfaces of the insulating block, rotation thereof and of the spring contacts is prevented and a very rigid structure 55 results which is quite simple to manufacture and to assemble, the whole contact assembly being held in position and together by the single screw 26.

The device as above described can be made 60 very compact and the porcelain is of such a shape as to enable it to be readily molded. By the use of a single screw for fastening both the contact and its binding post in position, cross strains are eliminated in the porcelain 65 and the chances of its breaking are very re-

mote, since the retaining screws place it under compression only. The device can be readily wired since the binding screws are on the sides, rather than on the back, as is common practice and hence a shallower box 70 can be used as well as a narrower and shorter one.

Having thus described the invention what is claimed as new and desired to be secured by Letters Patent is:

1. In an attachment plug receptacle, a base member including a one piece insulating block, a boss projecting from the front face thereof and provided with a pair of T-slots, each of said slots communicating with a separate recess in said block, a partition separating said recesses longitudinally, each recess opening directly and fully only into a side face of said block and said block being provided with restricted bores connecting said 80 recesses with the face opposite said boss. 85

2. In an attachment plug receptacle in combination, a one piece insulating block having slots in the front face thereof communicating each with a recess in said block, said recesses being completely separated from each other and opening to their full area only on alternate sides of said block, a contact member in each recess, a circuit terminal connected to each contact and extending outside 90 of its recess through said opening and along the side face of said block. 95

3. In an attachment plug receptacle, in combination, a one piece insulating block having slots in one face thereof communicating each with a recess in said block, said recesses being completely separated from each other and opening fully on alternate sides of 100 said block, a contact member in each recess, a base on each contact member, a circuit terminal extending into each recess and overlying said base, and a screw passing into said recess through said contact and into said terminal to secure these parts together and in 105 said recess. 110

4. In an attachment plug receptacle, in combination, a one piece insulating block having slots in one face thereof communicating each with a recess in said block, said recesses being completely separated from each other and opening on alternate sides of said block, a contact member in each recess, a base on each contact member, a circuit terminal extending into each recess and overlying said base, a screw passing into said recess and securing said contact and terminal together and in said recess, said circuit terminals extending in opposite directions from said recesses, binding screws in said terminals, said binding screws being substantially in axial alignment. 115 120 125

5. In an attachment plug receptacle, in combination, a one piece insulating block having slots in one face thereof communicating each with a recess in said block, said recesses 130

being completely separated from each other and having their main openings on alternate sides of said block, a contact member in each recess, a base on each contact member, a circuit terminal extending into each recess and overlying said base, a screw passing into said recess and securing said contact and terminal together and in said recess, said circuit terminals extending in opposite directions from said recesses, binding screws in said terminals, one wall of each recess being grooved to receive the ends of the binding screws.

6. In an attachment plug receptacle, in combination, a one piece insulating block, a boss projecting from the center of one face thereof, mounting arms secured to said face beyond said boss, said boss having a pair of T slots therein communicating with recesses in said block, said recesses having top and bottom walls defined by said boss and block respectively and opening on opposite sides of said block, a partition isolating said recesses, a three armed contact member in each recess, a terminal member for each contact, an angled tab thereon, a perforated base on said contact member resting on the bottom wall of said recess, said tab overlying said base and engaging two of said arms, a screw passing through said block and base and into said tab, and a binding screw passing through each terminal member and into a groove in the partition.

7. In an attachment plug receptacle, in combination, an insulating block adapted to be received in a wall box, a projecting boss on the front thereof provided with a pair of plug prong receiving passages, said block having a separate recess below said boss for each passage and in communication therewith, each recess opening to substantially its full area only through a side face of said block and the two recesses having their openings oppositely directed, a prong receiving contact in each recess and a circuit terminal connected to each contact and passing through its respective side opening and being arranged outside of the block.

In testimony whereof I hereunto affix my signature.

50 HARRY J. MOREY.
